UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

THERMOSTATIC ELECTRIC SWITCH.

1,263,568.

Specification of Letters Patent. Patented Apr. 23, 1918.

Application filed January 18, 1917. Serial No. 143,157.

To all whom it may concern:

Be it known that we, FRANK KUHN and JAY A. HAND, both citizens of the United States of America, residing at Detroit, in the county of Wayne and State of Michigan, have invented certain new and useful Improvements in Thermostatic Electric Switches, of which the following is a specification, reference being had therein to the accompanying drawings.

The invention relates to thermostats more particularly designed for use in connection with electrically heated warming pads, and it is the object of the invention to obtain a simple construction for manufacture and one which is easily adjusted and maintained in operative condition.

In the drawings:

Figure 1 is an enlarged longitudinal section through the thermostat;

Fig. 2 is a perspective view of the parts detached.

Fig. 3 is a perspective view of the thermostat when detached from the casing.

A is a flat metallic strip having placed upon opposite sides thereof facings B and B' of insulating material, preferably of mica. C and C' are composite strips or thermostatic bars which are secured on opposite sides of the bar A by suitable means, such as the rivets D passing through apertures E in the bar A. The arrangement is such that each of the strips C and C' is insulated and is at the same time securely attached at one end to the bar A. F is an adjusting screw, having a threaded engagement with one of the thermostatic bars C and passing through an aperture G in the bar A and insulating facings into contact with the other of the thermostatic bars. Non-corrodible points of platinum or other suitable material are placed upon the adjusting screw F and the other thermostatic bar, as indicated at I and I'. J is a section of tubing forming a housing for the thermostat, being of an internal diameter corresponding to the width of the bar A whereby the latter is supported longitudinally centrally of the former and the thermostatic bars are prevented from engaging the casing. The length of this tubular casing is such as to inclose the movable portions of the thermostatic bars, but a shank portion of each of these bars preferably extends be-

yond the casing and is provided with a screw K or other means of attaching the resistor terminal thereto. The casing J is also provided with an aperture L having a flange or nipple M surrounding the same and forming a guard for the adjustable screw F.

With the construction as described, the two thermostatic bars arranged upon opposite sides of the supporting bar A will double the amount of movement, while the screw F may be adjusted so that the circuit will be opened or closed at any desired point. As all of the elements are formed either of flat strips or plain tubing the construction is exceedingly simple and inexpensive to manufacture.

What we claim as our invention is:

1. A thermostatic electric switch, comprising a flat supporting bar having insulating facings on opposite sides thereof, a pair of thermostatic bars on opposite sides of the supporting bar, secured thereto and insulated therefrom by said facings, and cooperating contacts on the adjacent ends of said thermostatic bars engageable with each other through an aperture in said supporting bar.

2. A thermostatic electric switch, comprising a flat metallic supporting bar, insulating facings on opposite sides of said bar, flat thermostatic bars mounted upon opposite sides of said supporting bar, secured thereto and insulated therefrom and having their inner ends overlapping, and a contact member adjustably secured to one of said thermostatic bars, extending through an aperture in the supporting bar and insulating facings into engagement with the opposite thermostatic bar.

3. A thermostatic electric switch, comprising a flat metallic supporting bar, insulating facings on opposite sides thereof, flat thermostatic bars secured to and insulated from opposite ends of said supporting bar, the inner ends of said thermostatic bars overlapping, an adjustable contact member on one of said thermostatic bars, passing through an aperture in said supporting bar into engagement with the other of said thermostatic bars, and a cylindrical casing of a diameter corresponding to the width of said supporting bar, inclosing the same and the thermostatic bars.

4. A thermostatic electric switch, comprising a tubular casing, a flat bar of a width corresponding to the internal diameter of said tubing and extending longitudinally thereof, and therethrough, and thermostatic bars mounted on said supporting bar housed within said tubing and adapted to engage each other.
5. In a thermostatic electric switch, a tubular housing, a flat metallic bar of a width corresponding to the internal diameter of said housing, extending longitudinally centrally therethrough, thermostatic bars secured to and insulated from said supporting bar on opposite sides thereof, and an adjustable contact member insertible through an aperture in said tubular housing into engagement with one of said thermostatic bars and passing through an aperture in said supporting bar into engagement with the opposite thermostatic bar.
6. A thermostatic electric switch, comprising a tubular casing, a bar of a width corresponding to the internal diameter of said
- tubing and extending longitudinally thereof, a thermostatic bar mounted on said bar at one side thereof, a second bar mounted on said first mentioned bar at the opposite side thereof and contacts on said bars adapted to engage each other.
7. A thermostatic electric switch, comprising a tubular casing, a flat bar of a width corresponding to the internal diameter of said tubing and extending longitudinally thereof, a thermostatic bar mounted on said flat bar at one side thereof, a second bar mounted on said flat bar at the opposite side thereof, an adjustable contact on one of said bars, adjustable from without said tubular casing.

In testimony whereof we affix our signatures in presence of two witnesses.

FRANK KUHN.
JAY A. HAND.
